UNITED STATES PATENT OFFICE

2,061,406

BUTTER TUB DISPLAY SUPPORT

Charles Raffa, Brooklyn, N. Y.

Application July 20, 1935, Serial No. 32,333

3 Claims. (Cl. 312—116)

This invention relates to improvements in display supports and more particularly to a sanitary support for butter tubs.

One of the principal features of the invention resides in a display support for dairies, grocery stores, delicatessen stores or the like for supporting the open end of a butter tub in an easily accessible position within an ice box or refrigerator compartment, and for closing the space between the walls of the door opening of the ice box or refrigerator to prevent the entrance of hot air into the refrigerator compartment during the opening of the compartment door which is necessary to gain access thereto for dispensing of butter from the tub.

Another feature of the invention is to provide a sanitary display support which supports the butter tub in a forwardly tilted position to facilitate easy access to the open end of the butter tub when dispensing butter therefrom.

A further object of the invention is the provision of a butter tub support which is simple and inexpensive of construction, easy to clean in order to maintain the same in a sanitary condition, and adaptable for use in conjunction with ice boxes and refrigerators now in use.

Other features of the invention will appear as the following specification is proceeded with and when read in conjunction with the accompanying drawing, in which:

Figure 1 is a fragmentary front elevation of an ice box or refrigerator showing the invention in use therewith, the refrigerator compartment door being shown open.

Figure 2 is a vertical sectional view on the line 2—2 of Figure 1, but showing the refrigerator door in closed position.

Figure 3 is an enlarged vertical sectional view through the mid-portions of the support with the end of a butter tub seated thereon.

Figure 4 is a perspective view of the butter tub support per se.

Referring to the drawing by reference characters, the numeral 10 designates the butter tub display support in its entirety and which is shown as being constructed from a single sheet of metal bent into the form to be presently explained. Any rigid material may be employed in the construction of the support, but for sanitary reasons, it is preferable to construct the same of porcelain, Monel metal or the like. The support 10 includes a pair of end walls or flanges 11—11 which are connected by an inclined panel or front wall 12, the said wall having a central circular opening 13 therein of a size to snugly re-

ceive the open end of a butter tube to be supported. Extending from the panel 12 outwardly from that side opposite from which the flanges or end walls 11—11 extend, is a semi-circular shaped flange or rest 14. The rest 14 extends approximately about the lower half of the opening 13 and projects from the walls of the opening 13.

Extending outwardly at an angle from the panel 12 on that side joined by the end walls 11—11, is a bottom flange or ledge 15 which extends the width of the panel 12 and joins the bottom of the end walls 11—11.

In Figures 1 and 2 of the drawing, I have illustrated the invention in use, wherein a fragmentary portion of an ice box or refrigerator 16 is shown, the same having a refrigerator compartment 17 accessible through a door opening 18 in the front of the refrigerator and which opening may be closed by vertically sliding door 19.

The shape of the door opening 18 shown in the drawing is substantially rectangular, and therefore the panel 12 is of a like shape and size to snugly fit within the walls of the opening 18, with the ledge 15 resting upon the bottom of the compartment 17 and the vertical straight edges of the end walls 11 being disposed parallel with the path of movement of the door 19 but out of the path of movement thereof so as not to interfere with the free sliding movement of the door to open and closed position. The top edges of the end walls 11 and panel 12 fit against the side walls and top wall respectively of the door opening 18, thus a support 10 fills the space of the door opening. When the support 10 is in this position, the panel 12 is disposed in an upwardly and rearwardly inclined position as shown in Figure 2 for the purpose of supporting the butter tub 20 in a forwardly tilted position. The open end of the butter tub 20 extends through the opening 13 and rests upon the flange 14. The open end of the butter tub serves to close the opening 13 and to expose the open end of the butter tub for the dispensing of the same upon the opening of the door 19.

From the foregoing description, it will be seen that the butter tub 20 is supported with its open end facing the door opening 18 and with its opposite end resting upon the bottom of the refrigerator compartment 17. Any particles of butter which may accidentally drop from the open end of the tub during dispensing of the butter will be caught upon the ledge 15, which ledge is kept in a sanitary condition at all times.

When it is desired to clean the refrigerator

compartment 17, the support 10 may be removed from the door opening to enable free access to the compartment. Also, the removal of the support permits of the thorough cleansing of the 5 same in order to maintain the support in a sanitary condition.

When a butter tub is in a supported position within the support 10, the support serves to close the space between the butter tub and the walls 10 of the door opening to exclude the entrance of hot air into the refrigerator compartment 17 when the door 19 is opened to gain access to the butter tub for the dispensing of butter therefrom.

15 The top of one of the end walls 11 may be cut away as at 21 to form a ledge upon which a receptacle may be hung for the support of a butter knife or other implements used in the dispensing of butter from the tub.

20 While I have shown and described what I consider to be the most practical embodiment of my invention, I wish it to be understood that such changes as come within the scope of the appended claims may be resorted to if desired.

25 Having thus described the invention, what I claim as new and desire to secure by Letters Patent of the United States, is:—

1. A tub display support comprising a flat panel of a size and shape to fit into and close the

door opening of a refrigerator compartment, said panel having an opening therein to receive the open end of a tub, end flanges extending angularly and forwardly from said panel, and a bottom flange extending forwardly from said panel and connecting the lower ends of said end flanges.

2. A tub display support comprising a flat panel of a size and shape to fit into and close the door opening of a refrigerator compartment, said panel having an opening therein to receive the 10 open end of a tub, end flanges extending angularly and forwardly from said panel, a bottom flange extending forwardly from said panel and connecting the lower ends of said end flanges, and a flange extending rearwardly of said panel 15 from the lower half of the walls of said opening.

3. A tub display support constructed of a single sheet of material comprising a rearwardly inclined panel of a shape to snugly fit within the walls of the door opening of a refrigerator compartment and having a central opening therein, a tub supporting flange extending rearwardly from said panel from the lower half of the walls of said opening, end walls extending forwardly from the side edges of said panel and extending the height thereof, and a spillage ledge extending forwardly from said panel at the bottom edge thereof with its ends meeting said end walls.

CHARLES RAFFA.
